UNITED STATES PATENT OFFICE.

SETH A. CRONE, OF EAST ORANGE, NEW JERSEY.

BRAKE BEAM.

1,142,498.

Specification of Letters Patent. Patented June 8, 1915.

Application filed March 8, 1915. Serial No. 12,868.

To all whom it may concern:

Be it known that I, SETH A. CRONE, a citizen of the United States, and a resident of East Orange, in the county of Essex and State of New Jersey, have invented certain new and useful Improvements in Brake-Beams, of which the following is a specification.

The invention pertains more particularly to trussed beams and especially to a novel strut and connections for such beams.

In accordance with my invention I provide a one-piece forged metal strut at one end receiving the compression member of the beam and at the other end having secured thereto a cap or socket of special configuration adapted to the tension member and to strengthen the strut and aid in securing the two side members of the strut in due relation to each other.

The purpose of the invention is not only to provide a strut capable of being manufactured in one piece from forged metal, but also one which may be conveniently applied to position and be highly efficient in use as well as durable for the purposes intended.

The invention will be fully understood from the detailed description hereinafter presented, reference being had to the accompanying drawings, in which:

Figure 1 is a vertical section through a brake beam taken along the edge of the strut and therefore showing the strut in horizontal side elevation; Fig. 2 is a vertical transverse section through the same, taken on the dotted line 2-2 of Fig. 1; Fig. 3 is a vertical transverse section through a modified construction of strut, this section being taken through the strut near the outer end thereof and the modification residing mainly in convexing outwardly the sides of the strut and conforming the end cap or socket for the strut to receive such sides, and Fig. 4 presents a suitable construction of cap for the outer end of the strut.

In the drawings, 10 designates the compression member, 11 the truss rod or tension member, and 12 the strut, this strut being formed from a single piece of forged metal folded at its center and extending transversely around and engaging the compression member 10 and carrying at the outer or free ends of its sides a metal socket 13 adapted to receive and secure such ends and also to engage the truss rod 11. The compression member 10 may vary in cross-sec-

tion, but I prefer to use a channel beam for the member 10, as I illustrate in Fig. 1.

The strut 12 is, as shown, formed from a single bar of forged metal folded at its middle portion to form a box-loop 14 adapted to encompass the outer surfaces of the member 10, whence the body portions of the folded bar are correspondingly deflected to form the parallel angular sides 15 adapted to receive between them in the usual manner the customary brake lever, not shown. The sides 15 extend parallel with each other to their outer or free ends, and upon said ends is applied the cap or socket member 13, which may be a malleable casting, a drop forging, or other metal, having at its outer end a groove 16 to transversely receive the middle portion of the truss rod 11 and at its inner portion an inclosing flange 17 which receives the free ends of the sides of the strut and a filler section 18 adapted to fill in the space between the outer ends of said sides, grooves being formed between said filler section 18 and the adjacent longer sides 15 of the cap or socket 13 into which the outer ends of the sides 15 are securely held. The cap or socket 13 on its longer sides is formed with sections 19 which engage the outer surfaces of the strut sides 15 and are parallel with the filler section 18. The cap or socket 13 receives between the sections 19 and opposite sides of the filler 18 the outer ends of the sides 15 and finally said sides and said cap or socket are rigidly secured together by a rivet 20 passing through the cap or socket sections 19, strut sides 15 and filler 18. The sides 15 adjacent to the inner edges of the beam 10 receive between them a filler 21 through which and said sides extends a rivet 22, the latter with the rivet 20 serving to secure the two sides of the strut together and with the filler parts 18 and 21, maintain said sides in due relation to each other. The strut sides 15 are at a suitable point between the ends of the strut transversely apertured; as at 23, to receive the brake lever pin, not shown, and surrounding the apertures 23 are flanges 24 pressed up from the material of the sides 15 to afford increased strength and a proper bearing for the brake lever pin.

I shall preferably form longitudinal corrugations 25 in the sides 15 between the flanges 24 and cap or socket 13, one corrugation being formed in each side and convexed outwardly therefrom, in the manner I

indicate in Fig. 3 in a modification, so as to strengthen the sides 15 in their outer portions which in use are under compression. The corrugations 25 may extend simply between the flanges 24 and cap or socket 13, or they may continue, as I show in Fig. 3, into the end cap or socket.

Since Fig. 3 illustrates a modification I number the sides of the strut 26, the corrugations in said sides 27, the end cap or socket 28, the filler contained in said cap or socket and extending between the strut sides 29 and the encompassing flange of the cap or socket 30. Fig. 3 is meant to illustrate that I may extend the corrugations 25 of Fig. 1 into the end cap or socket or omit to do so, as I may prefer, increased strength to resist compression being gained when the corrugations do extend into the end cap or socket. The cap or socket 28 is also illustrated in Fig. 4, and said cap or socket may be provided with eyes 31 to receive the usual suspension hanger.

I preferably cause the box loop member 25 to closely bind against the compression member 10, and in addition it will be found desirable to additionally secure said box loop member to the compression member by means of a rivet 32, as shown in Fig. 1, the rivet extending horizontally through the outer member of the beam 10 and the metal portion of the outer member of the box loop 14.

The essential features of my invention reside in the strut hereinbefore described in connection with the cap or socket and other features referred to, the object being to, without undue weight or waste of metal, provide a truss beam construction having a forged strut of highly efficient and durable character and capable of ready manufacture.

What I claim as my invention and desire to secure by Letters Patent, is:

45 1. A trussed brake-beam comprising a compression member, a tension member and a strut intermediate said members for the brake-lever, said strut being a forged metal folded bar having at its fold a box-loop encompassing said compression member whence the members of the bar are deflected forming angularly disposed parallel sides extending to the outer end of the strut, and a cap-socket on the outer ends of said sides 55 having a bearing for the tension member, sockets for the ends of said sides and means to receive a rivet for securing the cap-socket to said sides.

2. A trussed brake-beam comprising a compression member, a tension member and a strut intermediate said members for the brake-lever, said strut being a forged metal folded bar having at its fold a box-loop encompassing said compression member whence the members of the bar are deflected

forming angularly disposed parallel sides extending to the outer end of the strut, and a cap-socket on the outer ends of said sides having a bearing for the tension member, sockets for the ends of said sides and means to receive a rivet for securing the cap-socket to said sides, said sides in their outer end portions being longitudinally corrugated.

3. A trussed brake-beam comprising a compression member, a tension member and a strut intermediate said members for the brake-lever, said strut being a forged metal folded bar having at its fold a box-loop encompassing said compression member whence the members of the bar are deflected forming angularly disposed parallel sides to the outer end of the strut, and a cap-socket on the outer ends of said sides having a bearing for the tension member, sockets for the ends of said sides, a spacing portion fitting between said ends and means for securing the cap-socket to said sides.

4. A trussed brake-beam comprising a compression member, a tension member and a strut intermediate said members for the brake-lever, said strut being a forged metal folded bar having at its fold a box-loop encompassing said compression member whence the members of the bar are deflected forming angularly disposed parallel sides extending to the outer end of the strut, and a cap-socket on the outer ends of said sides having a bearing for the tension member, a flange encompassing the outer ends of and connecting said sides, a spacing portion fitting between said ends, and means to receive a rivet for securing the cap-socket to said sides.

5. A trussed brake-beam comprising a compression member, a tension member and a strut intermediate said members for the brake-lever, said strut being a forged metal folded bar having at its fold a box loop encompassing said compression member whence the members of the bar are deflected forming angularly disposed parallel sides extending to the outer end of the strut, and a cap-socket on the outer ends of said sides having a bearing for the tension member and sockets for the separated ends of and secured to said sides, said compression member being a channel beam and said box-loop being secured thereto by a rivet extending through the outer vertical member of said loop and the adjacent portion of said beam.

6. A trussed brake-beam comprising a compression member, a tension member and a strut intermediate said members for the brake-lever, said strut being a forged metal folded bar having at its fold a box-loop encompassing said compression member whence the members of the bar are deflected forming angularly disposed parallel sides extending to the outer end of the strut, and

a cap-socket on the outer ends of said sides having a bearing for the tension member and sockets for the separated ends of and secured to said sides, said sides adjacent to 5 the compression member having between them a separating piece and a rivet extending through the same and said sides.

Signed at New York city, in the county of New York and State of New York, this 5th day of March A. D. 1915.

SETH A. CRONE.
